U.S. PATENT DOCUMENTS

FIG. 1 is a top perspective view of a closure, showing our new design;

D95,675 S *	5/1935	Fuerst	.....	D9/453
3,796,338 A *	3/1974	Wilton	.....	215/252
4,402,418 A	9/1983	Ostrowsky		
4,458,821 A	7/1984	Ostrowsky		
4,458,822 A	7/1984	Ostrowsky		
4,470,513 A	9/1984	Ostrowsky		
4,478,343 A	10/1984	Ostrowsky		
4,801,030 A	1/1989	Barriac		
4,801,031 A	1/1989	Barriac		
4,978,016 A	12/1990	Hayes		
4,997,097 A	3/1991	Krautkramer		
5,007,545 A	4/1991	Imbery, Jr.		
5,058,755 A	10/1991	Hayes		

FIG. 2 is a top plan view of the claimed design of FIG. 1;

FIG. 3 is a bottom plan view of the claimed design of FIG. 1;

FIG. 4 is a front elevational view of the claimed design of FIG.

1, the rear elevational view being the same as the front elevational view;

FIG. 5 is a left side elevational view of the claimed design of FIG. 1, the right side elevational view being a mirror image of the left side elevational view;

FIG. 6 is a sectional view of the claimed design of FIG. 1, taken along line 6-6 of FIG. 3; and,

FIG. 7 is bottom perspective view of the claimed design of FIG. 1.
